UNITED STATES PATENT OFFICE.

KATE D. BALDWIN, OF WHITE PLAINS, NEW YORK, ASSIGNOR TO GEORGE K. BALDWIN, OF LOS ANGELES, CALIFORNIA.

SUPPORTING WAIST.

Application filed March 7, 1927. Serial No. 173,283.

Heretofore children's underwaists or supporting jackets have been made with the buttons usually sewed onto the lower hem of the waist or jacket to permit trunks, underpants, petticoats, or the like to be removably buttoned thereto. This arrangement has proven unsatisfactory due to the fact that when a child wearing one of the supporting waists bends over a strain is transmitted from the supporting buttons to the material on which the buttons are sewed. The material after a very short time is thus easily torn or the buttons pulled off due to the lack of sufficient give in the material to compensate for the strains applied thereto.

This invention has been developed to provide an improved type of supporting jacket or underwaist which is so constructed with reinforcing tapes and with plaited sections in the rear portion to permit the plaited portions to be extended when a person wearing an improved waist of this type bends over, thereby obviating undue strains on the supporting buttons and on the goods due to the fact that the plaited portions relieve said goods and the buttons from undue tensional strains.

It is an object of this invention to provide a child's supporting waist with a plurality of reinforcing tapes on the back portion dividing the back portion into sections between which the material forming said sections is transversely plaited to permit the sections to be temporarily extended longitudinally when strains are applied to the rear sections by a lower garment buttoned onto the waist.

It is also an object of this invention to provide a child's underwaist with plaited sections having supporting buttons mounted thereon, permitting a lower garment to be buttoned to the waist, the plaited portions of said waist being adapted to stretch when a child bends over to relieve the material of undue tensional strains, thereby prolonging the life of the underwaist.

It is an important object of this invention to provide a child's supporting waist reinforced with tapes dividing the rear portion of the waist into a plurality of sections which are plaited above a circumferential strip or tape girdle on which supporting buttons are suspended by means of tape loops, thereby permitting a lower garment to be engaged on said buttons, allowing the

child to bend without danger of applying undue tensional strains to the material forming said sections, thereby obviating tearing of the material and pulling off of buttons.

Other and further important objects of 60 this invention will be apparent from the disclosures in the specification and the accompanying drawings.

This invention (in a preferred form) is illustrated in the drawings and hereinafter 65 more fully described.

On the drawings:

Figure 1 illustrates a boy wearing an improved supporting waist embodying the principles of this invention. 70

Figure 2 illustrates a boy bending over, illustrating the elongated position of the waist sections caused by the strains applied thereto by a pair of trousers attached to the waist buttons and illustrated in dotted lines. 75

Figure 3 is an enlarged developed plan view of the supporting waist.

Figure 4 is a fragmentary detail plan view of the lower rear portion of the waist showing the position of an extensible section when 80 a pull is applied thereto.

Figure 5 is an enlarged fragmentary detail section taken on line V—V of Figure 3.

As shown on the drawings:

The reference numeral 1 indicates a boy or 85 child wearing an improved supporting waist embodying the principles of this invention and comprising front side sections 2 and 3 connected by a back section 4 and intermediate back sections 5 and 6. The front side 90 sections are connected to the back sections by means of shoulder straps 7. The front section 3 is provided with a hem 8 having a plurality of button holes 9 therein. The opposite front section 2 is provided with a reinforcing hem 10 on which buttons 11 are sewed for use with the button holes 9 so that the waist when worn by a child may be buttoned down the front of the child. 95

The improved supporting waist is provided with a pair of rear reinforcing tapes or straps 12 extending from the shoulder straps 7 downwardly to the lower hem of the waist. The reinforcing tapes 12 are stitched in position and divide the back waist section 4 from the two side rear sections 5 and 6. A reinforcing tape 13 is stitched in place between the waist sections 3 and 6 and extends from the arm hole downwardly to a circumferential or belt tape 14 stitched 110

around the exterior of the lower portion of the waist a short distance above the lower hem of said waist. Another reinforcing tape 15 separates the waist sections 2 and 5 and extends from the second arm hole downwardly to the belt tape 14. Secured to the belt tape 14 at spaced intervals are a plurality of tape loops 16 a bight portion of each of which is engaged through a button 17 to hold each of the buttons suspended from the belt tape beneath which the ends of the button supporting loops 16 are fastened or sewed.

The three back sections 4, 5, and 6 forming the back of the waist are each provided with a transverse open plait or fold 18 directly above the belt tape 14 with the ends of said plaits sewed under the respective reinforcing tapes 12, 13, and 15.

20 The novel construction of the improved supporting waist or underjacket equipped with the open folds or plaits 18 in the back panel sections between the reinforcing tapes 12, 13, and 15 and above the belt tape 14 affords an arrangement whereby the back sections are permitted to be elongated or stretched due to the opening of the plaits 18, as illustrated in Figures 2 and 4, when the person wearing the waist bends over and a 25 pull is exerted on the rear supporting buttons of the waist by the trousers 19 or any other lower garment attached or buttoned onto the supporting waist. It will thus be seen that with the extension plaits 18 provided as described that when a person bends the goods forming the back of the underwaist is relieved of any undue strains or pulls so that the material forming the waist is not torn nor are the buttons pulled off. A 30 very durable and strong underwaist is thus provided having the plaited or shirred portions in the back sections serving to allow stretching of the back waist sections when necessary, thereby saving said sections from 35 tearing. The improved underwaist equipped with the extensible plaits also affords a garment which can be worn with a great deal of ease and convenience.

I am aware that many changes may be 50 made, and numerous details of construction may be varied through a wide range without departing from the principles of this invention, and I therefore do not purpose limiting the patent granted hereon, otherwise than necessitated by the prior art.

I claim as my invention:

60 1. A supporting waist comprising a jacket constructed to be buttoned down the front, a waist band secured to said jacket above the lower margin thereof, a plurality of loops secured to said waist band, buttons mounted with the bights of said loops projecting through the holes of said buttons, a plurality of reinforcing tapes longitudinally secured on the back portion of the jacket ex-

tending from the upper portions of the jacket downwardly to divide the rear portion of the jacket into a plurality of sections, and transverse plaits in said sections above the waist band and between said reinforcing tapes. 70

2. A supporting waist of the class described comprising a jacket constructed to be buttoned down the front and having shoulder straps forming a part thereof, a waist band secured to said jacket, buttons suspended from said waist band, a plurality of reinforcing tapes extending longitudinally from the upper portion of the waist downwardly and stitched their entire length to divide the 80 back of the waist into a plurality of sections, and plaits in said sections to permit the sections separated by said tapes to be independently elongated without straining the material when a person wearing the 85 jacket bends.

3. A supporting waist of the class described comprising back and front side sections, a waist band secured across said back and side sections, loops secured to said waist band, buttons supported on said loops, a plurality of tapes stitched for their entire length longitudinally on said back dividing the same into a plurality of sections, and independently extendible means formed in each 90 of said back sections to permit said back sections to be independently elongated when a pull is applied to said waist band by a garment supported by said buttons.

4. A supporting waist comprising a jacket 100 constructed with shoulder straps and adapted to be buttoned down the front, a plurality of reinforcing tapes stitched to the back of the jacket and extending from the upper portion of said back downwardly toward the bottom dividing the back into a plurality of sections, plaits formed in said back sections with the ends of said plaits closed by stitching passing through said 105 tapes permitting the back sections to be elongated when a pull is exerted on the lower ends thereof, and garment supporting means 110 between the reinforcing tapes and below said plaits.

5. A supporting jacket comprising a waist 115 adapted to be buttoned down the front, a plurality of tapes stitched longitudinally on the back of said waist, and plaits formed transversely in said back between said tapes and closed at their ends by said stitching to 120 permit the back to be elongated without subjecting the material forming the back to tearing strains.

6. A supporting waist comprising a jacket having a plurality of tapes stitched longitudinally and transversely of the back to divide the back into a plurality of sections, buttons carried by said sections, and a plurality of aligned plaits formed in said sections between said longitudinally disposed 130

tapes and stitched thereto to permit said sections to be elongated when pulling strains are applied to the buttons.

band to permit the back section of the jacket 10 to be elongated, and reinforcing members stitched their entire length to said back section dividing the plait into sections.

7. A supporting waist comprising a jacket 5 constructed to be buttoned down the front, a waist band secured to said jacket, a plurality of loops suspended from said waist band, buttons carried by said loops, a plait in the back portion of said jacket above the waist

In testimony whereof I have hereunto subscribed my name at White Plains, West- 15 chester County, New York.

KATE D. BALDWIN.
